(57) **CLAIM**

The ornamental design for a body frame as shown and described.

DESCRIPTION

FIG. 1 is a top, right, front perspective view of a body frame showing our new design.

FIG. 2 is a front view thereof;

FIG. 3 is a rear view thereof;

FIG. 4 is a right side view thereof;

FIG. 5 is a left side view thereof;

FIG. 6 is a top side view thereof; and,

FIG. 7 is a bottom side view thereof.

The broken lines shown in the Figures show elements of the body frame that form no part of the claimed design. The shade lines in the Figures show contour and do not claim surface ornamentation or treatment.
